(57) **CLAIM**

The ornamental design for a lighting fixture, as shown and described.

DESCRIPTION

FIG. 1 is a front perspective view showing a new design for a lighting fixture;

FIG. 2 is a front view of the lighting fixture of FIG. 1;

FIG. 3 is a rear view of the lighting fixture of FIG. 1;

FIG. 4 is a right view of the lighting fixture of FIG. 1;

FIG. 5 is a left view of the lighting fixture of FIG. 1;

FIG. 6 is a top view of the lighting fixture of FIG. 1;

FIG. 7 is a bottom view of the lighting fixture of FIG. 1;

FIG. 8 is a front perspective view showing a new design for a lighting fixture;

FIG. 9 is a front view of the lighting fixture of FIG. 8;

FIG. 10 is a rear view of the lighting fixture of FIG. 8;

FIG. 11 is a right view of the lighting fixture of FIG. 8;

FIG. 12 is a left view of the lighting fixture of FIG. 8;

FIG. 13 is a top view of the lighting fixture of FIG. 8; and,

FIG. 14 is a bottom view of the lighting fixture of FIG. 8.

The dashed lines showing portions of the lighting fixture are included for the purpose of illustrating environment and form no part of the claimed design.

1 Claim, 14 Drawing Sheets
